(57) **CLAIM**

The ornamental design of a wet wheel tile cutter, as shown and described.

DESCRIPTION

FIG. 1 is a right side view of a wet wheel tile cutter showing the new design;

FIG. 2 is a left side view thereof;

FIG. 3 is a top plan view thereof;

FIG. 4 is a bottom view thereof;

FIG. 5 is a rear view thereof; and,

FIG. 6 is a front view thereof.

The broken line showing is for illustrative purposes only and forms no part of the claimed design.
